UNITED STATES PATENT OFFICE.

JOSEPH SINGER, OF CHICAGO, ILLINOIS.

FRINGE.

SPECIFICATION forming part of Letters Patent No. 380,141, dated March 27, 1888.

Application filed March 29, 1887. Serial No. 232,838. (No model.)

To all whom it may concern:

Be it known that I, JOSEPH SINGER, of Chicago, county of Cook, and State of Illinois, have invented certain new and useful Improvements in Fringes, of which the following is a full, clear, and exact description, that will enable others to make and use the same, reference being had to the accompanying drawings, forming a part of this specification.

10 This invention relates, especially, to that class of fringe or trimming used by upholsterers as an ornamental border or finish, as will be hereinafter set forth.

Figure 1 is a front view of a piece of fringe embodying my improved features; Fig. 2, a 15 transverse section in the plane 2, Fig. 1.

The underskirt or web of the fringe A consists of a series of loose strands of worsted arranged side by side and woven together along 20 the upper edge by the warp-threads a a' , thus forming the selvage or head proper. The warp-threads a' form a second or double head. Below the double heading the strands of worsted are divided into bunches, which are 25 compressed near their longitudinal center by the tie-bands a^3 , leaving the space or opening a^4 between each two and forming the tassels or pendants b .

The overskirt consists of the cord b' , arranged in festoons, and the tassels or pendants 30

b^3 , composed of bunches of worsted doubled over the small loops b^3 in the festooned cord and woven into the underskirt by the warp-threads a^2 , thus saving the time and labor required in attaching them by hand, and also 35 preventing these parts from working laterally out of place relative to the lower fabric. The tassels b^4 are shorter than the companion tassels of the underskirt, and are arranged alternately relative thereto. By this arrangement 40 the parts forming the overskirt cannot change position nor become disarranged, as they are apt to do when simply looped around the festooned cord, without being woven into the fabric or groundwork.

Having thus described my invention, what I 45 claim as new, and desire to secure by Letters Patent, is—

A fringe consisting of an underskirt or web terminating in the tassels or pendants b , the 50 festooned cord b' , woven into the web by the warp-threads a' , and the over tassels or pendants b^4 , looped over the cord b' and woven to the underskirt by the warp-threads a^2 , whereby the parts are retained in their proper relative position, substantially as set forth.

JOSEPH SINGER.
